UNITED STATES PATENT OFFICE.

SIMON W. FARBER, OF BROOKLYN, NEW YORK, ASSIGNOR TO SIMON W. FARBER, INC., OF BROOKLYN, NEW YORK, A CORPORATION OF NEW YORK.

DESIGN FOR A HOLDER FOR GLASSES.

Application filed March 5, 1927. Serial No. 20,976. Term of patent 14 years.

To all whom it may concern:

Be it known that I, SIMON W. FARBER, a citizen of the United States of America, residing at Brooklyn, in the county of Kings, city and State of New York, have invented a new, original, and ornamental Design for Holder for Glasses, of which the following is a specification, reference being had to the accompanying drawing, forming a part thereof.

The drawing shows a perspective view of a holder for glasses, showing my new design.

I claim:

The ornamental design for a holder for glasses substantially as shown.

SIMON W. FARBER.
